UNITED STATES PATENT OFFICE.

HEINRICH RILLER, OF WUSTENBRAND, GERMANY.

VIOLIN LUTE.

Application filed November 1, 1926, Serial No. 145,600, and in Germany November 19, 1925.

This invention relates to a musical-instrument, which combines a lute and a violin. The violin-lute differs from the chord-string-instruments of known type by a novel arrangement of the melody strings. In zithers played with a bow having melody strings at both sides and chord strings in the middle the rows of bridge pins for the melody strings are arranged on the outer sides, i. e. parallel to the string wall of the instrument. At these places they are, however, in the way at the playing with the bow and further much lateral space is occupied by the same so that the number of melody strings is limited as otherwise the zither would become too wide. In the violin-lute according to the invention the row of bridge pins is arranged on the instrument parallel to the chord strings so that the above mentioned inconveniences are avoided.

An embodiment of the invention is shown, by way of example, in the accompanying drawing, in which

Fig. 1 shows an improved violin-lute in side elevation.

Fig. 2 is a plan view.

The hollow body 1 of the violin-lute has the shape of a lute. The chord strings 2 are arranged, as usual, in the middle and the melody strings 3 to be played are arranged at the right and left of the chord strings 2

so that the bow can be passed from right to left over all melody strings 3. In order to prevent that the row of bridge pins be in the way at the playing with the bow the bridge pins 8 for the melody strings 3 are arranged in one row at the side of the chord strings, i. e. on the inner side of the melody strings whereby more space is obtained in the direction of width of the instrument.

The sheet of music 4 is placed on bows 5 which bridge over the chord strings 2 so that the sheet is not in contact with the strings. The touching of the chord strings takes place on the lower end 6 of the violin-lute where a support 7 for the hand is arranged.

I claim:—

A violin-lute with chord strings on the middle and melody strings at either side of the chord strings comprising in combination with the chord strings arranged at the middle of the instrument, bridge pins arranged in one row at either side of said chord strings, and melody strings attached one to each bridge pin and extending in outwardly inclined direction to the lower end of the instrument where said inclining strings are attached.

In testimony whereof I affix my signature.

HEINRICH RILLER.
